COMBINED SAUCEPAN AND LID THEREFOR

Graham John Aries, Pedmore, Stourbridge, England, assignor to Tower Housewares Limited, Wombourne, Wolverhampton, Staffordshire, England

Filed Mar. 10, 1972, Ser. No. 233,857

Claims priority, application Great Britain Sept. 10, 1971

Term of patent 14 years

Int. Cl. D7—02

U.S. Cl. D7—95

FIG. 1

FIG. 2.

FIG. 3.

FIG. 4

FIG. 5

FIG. 6

FIG. 7

FIG. 8

FIG. 9

FIG. 1 is a top perspective view of a first embodiment of combined saucepan and lid therefor showing my new design;

FIG. 2 is a bottom perspective view;

FIG. 3 is a side elevational view;

FIG. 4 is a top perspective view of a second embodiment of combined saucepan and lid therefor showing my new design;

FIG. 5 is a bottom perspective view of the second embodiment;

FIG. 6 is a side elevational view of the second embodiment;

FIG. 7 is a top perspective view with the lid omitted for clarity of illustration;

FIG. 8 is a bottom perspective view with the lid omitted; and

FIG. 9 is a side elevational view with the lid omitted.

I claim:

The ornamental design for a combined saucepan and lid therefor, as shown and described.
